UNITED STATES PATENT OFFICE.

JOSEPH L. HERZOG, OF NEW YORK, N. Y.

DESIGN FOR A FINGER-RING.

No. 38,235.

Specification for Design.

Patented Sept. 11, 1906.

Application filed June 8, 1906. Serial No. 320,890. Term of patent 7 years.

To all whom it may concern:

Be it known that I, JOSEPH L. HERZOG, a citizen of the United States, and a resident of the city of New York, borough of Manhattan, in the county of New York and State of New York, have invented a new, original, and ornamental Design for a Finger-Ring, reference being had to the accompanying drawing, in which the figure is a perspective view

of a finger-ring embodying my new and ornamental design.

I claim—

The ornamental design for a finger-ring, as shown.

JOSEPH L. HERZOG.
